CASE SHIFT MECHANISM FOR TYPE-WRITERS AND LIKE MACHINES

William F. Helmond, Clinton, Conn., assignor to
Underwood Corporation, New York, N. Y., a
corporation of Delaware

Application December 8, 1949, Serial No. 131,824

3 Claims. (Cl. 197—81)

1

This invention relates to case-shift mechanisms for typewriters, and has reference particularly to the stops for arresting the shiftable member of the typewriter in either case position.

The invention is in the nature of an improvement in the case-shift stop described and claimed in the Helmond patent, No. 2,349,723, issued May 23, 1944, an object being to provide a stop element which in its cooperative function in the case-shift mechanism will assure quieter and more accurate limiting of case-shift movement.

Stop elements subjected to the frequent impact incident to case-shifting and constructed entirely or in substantial part of resilient material are apt to deteriorate or otherwise become deformed, and thus require fairly frequent replacement to maintain accurate case-shift. A further object of the invention is to provide a stop element which may be entirely devoid of resilient material such as rubber and the like, and yet will afford operating characteristics superior to stops comprising such materials.

Other objects will be in part obvious and in part particularly pointed out as the following description of a preferred embodiment of the invention proceeds.

In the drawings:

Fig. 1 is a fragmentary elevational view of a typical case-shift mechanism embodying the improved stop element of the invention.

Fig. 2 is a side elevational view taken on a plane indicated at line 2—2 of Fig. 1.

Fig. 3 is a perspective view of the case-shift stop element, and,

Fig. 4 is an exploded view of said element showing the component parts thereof.

Referring to the drawings, the case-shift mechanism embodying the invention as illustrated is substantially similar to that shown and described in said Patent No. 2,349,723. A segment frame 5 carries a type-bar segment 6 for pivotal support of a series of type-bars 7 having upper-and-lower case type adapted to strike a platen 8 upon shifting the frame 5 to either case position. The segment frame 5 is mounted for case-shift movement on the main frame of the typewriter, of which one side member 10 is shown. At its upper region the segment frame has roller-bearing units 11, and at its lower part is guided by arms 12 of a rockable shaft 13 pivoted on the main frame. Case-shift movement of the segment frame 5 is actuated by the usual shift lever, not shown, operatively connected to said frame by a link 14. A spring 15 yieldably holds the segment frame and

2

type-bar basket in the normal, that is lower-case position.

A stud 16 projecting laterally from the segment frame 5 provides pivotal attachment to said frame for the rock shaft arms 12 and extends beyond said arms to provide a bearing 17 on which a stop element, generally indicated at 18, is rotatably carried. At each limit of case-shift movement the stop element 18 engages confronting counterstops 20, each adjustably carried on the main-frame side member 10. This side member has a cut-out 21 from which lugs 22 are bent inwardly, each lug being threaded to receive the screw shank of one counterstop 20. The head of each counterstop presents a broad face for engagement with the stop element 18 and its edge may be knurled for convenience in adjusting the counterstops to the desired positions which determine the alignment of the upper and lower-case type with the typing line.

As shown best in Figs. 3 and 4, the stop element 18 comprises a block-like base or core member 23, a fabric sleeve 24 and a tension spring 25 or other suitable means for tensioning the sleeve so that it closely fits the core and is pressed firmly against the upper-and-lower faces 26, 27 thereof. These faces of stop element 18, with the portions of sleeve 24 overlying same, cooperate respectively with the counterstops 20 in limiting case-shift movement. In the preferred embodiment shown, the core 23 is a hollow box-like or tubular structure of rectangular cross section, open at each end. The tubular structure 23 may be formed for example by bending a flat strip of metal or similar material into that form as shown and, beside the top and bottom walls having the faces 26, 27, provides side walls 28. These side walls of core 23 each have a centrally disposed aperture 30 fitting the stud bearing 17 and therewith constitute a rockable mounting for the stop element 18 on the case-shiftable segment frame 5.

At one end of the core 23 the side walls 28 are extended to project beyond the adjacent edges of the top and bottom walls 26, 27 to provide lugs 31 which serve as shown in Fig. 3 to hold the fabric sleeve 24 from lateral displacement on the core. The opposite end of each side wall 28 has a hole to receive a hooked end of the spring 25, the free length of said spring between its hooks being somewhat shorter than the spacing between the walls 27 so that the spring 25 is under a slight tension when installed.

For best results the sleeve 24 is made up of a closely woven, relatively thin, fabric material

such as billiard cloth. Other materials, for example a good grade of sheet felt capable of withstanding the slight tension applied to the sleeve by spring 25, may also be used. A minimum thickness of the material for the sleeve 24 is preferable in order to minimize the extent to which the material is compacted incident to arresting case-shift movement; for which reason billiard cloth is preferable. However, a somewhat thicker sheet material such as felt may be suitable providing the same is closely felted so as to assure a minimum of compressibility under the pressure of case-shift arrest.

Although the preferred construction of the core 23 takes the form of a box-like or tubular structure, the same may be modified somewhat. For example, the core 23 may be formed of a solid block of rigid material having a bore such as at 30 and having a recess at one end to allow the fabric sleeve 24 to be tensioned so as to closely fit the core under influence of a suitable tensioning means such as spring 25. Further, although the lugs 31 are desirable, same may be omitted, the tension of sleeve 24 being depended on to maintain it frictionally against lateral displacement on core 23.

The manner of assembling the parts 23, 24 and 25 of the stop element 18 is shown in Fig. 4. The sleeve 24 is of such girth as to be readily insertable over the core 23, being passed without excessive stretching over the side lugs 31. With the sleeve thus in place the hooked ends of spring 25 are engaged in the smaller holes of the side walls 28, with the result that the body of the spring presses itself against the portion of sleeve 24 straddling the stop end between walls 26, 27. The hooked ends are formed on the spring 25 in such manner that when the spring is tensioned between the side walls 28 the coiled portion of the spring is substantially flush with the edges of the side walls, thus causing the adjacent area of sleeve 24 to be pressed into the hollow core as clearly shown in Fig. 3.

In the embodiment of the invention illustrated, the improved stop element is shown in a typewriter of the segment-shift or basket-shift kind wherein the shiftable member is the type-bar segment frame. It will be evident, however, that the invention is not limited to such kinds of typewriters but may be embodied in platen-shift type-writers as well.

I claim:

1. In a case-shift limiting means having two confronting counterstops, a stop element comprising a generally cubical core of rigid material and having opposite faces for cooperation respectively with the counterstops, a sleeve of fabric material surrounding said core so as to overlie the opposite faces and two ends of said core, at least one of said core ends having a recess, and a tension spring straddling said recess to depress the adjacent sleeve portion into the recess and thereby tension the sleeve into firm contact with the opposite faces of said core.

2. In a case-shift limiting means having two confronting counterstops, a stop element comprising a core composed of a metal tube of rectangular cross section, the top and bottom walls of said tube presenting outer faces for cooperation respectively with the counterstops, at least one tube end being open, a sleeve of fabric material surrounding said core over said faces and said tube ends, and a tension spring stretched between the side walls of the tube at said open end, the arrangement of said spring being such as to press the adjacent sleeve portion into said open end and thereby tension the sleeve into firm contact with the outer faces of said core.

3. In a case-shift limiting means having two confronting counterstops, a stop element comprising a box-like hollow core having an open end and having opposite faces for cooperation respectively with the counterstops, a sleeve of fabric material surrounding said core so as to overlie the opposite faces and two ends of said core, and spring means acting on the sleeve portion straddling the open core end to draw said portion inwardly of the core and thereby cause the sleeve to firmly engage the opposite faces of said core.
